UNITED STATES PATENT OFFICE.

FRANK KRATKY, OF NEW YORK, N. Y.

LIFE-BOAT OUTRIGGER.

1,127,901.

Specification of Letters Patent.

Patented Feb. 9, 1915.

Application filed July 20, 1914. Serial No. 851,986.

To all whom it may concern:

Be it known that I, FRANK KRATKY, a subject of the Emperor of Austria-Hungary, residing at New York, in the county 5 of New York and State of New York, have invented certain new and useful Improvements in Life-Boat Outriggers, of which the following is a specification.

This invention relates to new and useful improvements in life boat outriggers.

The primary object of this invention is to provide an outrigger float mechanism for boats, such as row boats and life boats, the same being foldable against the gunwale portions of the boat when not in use.

A further object is to provide upon each gunwale of the boat a pair of separating pivoted arms having a slidably float positioned therebetween adapted upon a ratchet-20 ing outward movement thereof to retain the outrigger in its operative position, the float being automatically withdrawn to the side of the boat upon a folding of the arms to the inoperative position of the outrigger.

A still further object is to provide a slid-25 able float having a ratchet connection with the side arms of an outrigger, the ratchet mechanism having a releasing device for allowing an inward movement of the float 30 while the latter is capable of oscillating when in its operative position upon the water.

With these general objects in view and others that will appear as the nature of the 35 invention is better understood, the same consists in the novel combination and arrangement of parts hereinafter fully described, illustrated in the accompanying drawings and pointed out in the appended 40 claims.

In the drawings forming a part of this application and in which like designating characters refer to corresponding parts throughout the several views:—Figure 1 is 45 a top plan view of a boat provided with the present device, one of the outriggers being shown operatively positioned and the other inoperatively folded. Fig. 2 is a front view of the same. Fig. 3 is a top plan view

of the connecting portions of one of the 50 outriggers shown upon an enlarged scale. Fig. 4 is a sectional view upon line IV—IV of Fig. 3. Fig. 5 is a top plan view of one of the outrigger arms detached. Fig. 6 is a top plan view of one of the floats de-55 tached and partially broken away and with a portion of one of the outrigger arms en-gaged thereby. Fig. 7 is a front elevation thereof, and Figs. 8 and 9 are enlarged detail views of the ratchet releasing means. 60

Referring more in detail to the drawings, the boat 10 is herein illustrated as provided with the oppositely positioned outriggers mounted adjacent the gunwales 11 of the boat by means of opposite brackets 12 which 65 are seated over said gunwales and have depending plates 13 flatly engaging the outer surface of the hull and also having inwardly projecting arms 14 which are united together by means of a shiftable set 70 collar 15. Each of the brackets 12 is pro-75 vided on its outer side and adjacent its op-posite ends with a hinging pintle 16 upon each of which pintles there is pivoted an arm 17 of the form illustrated in Fig. 5. The arms 17 are each provided at their outer ends with a float 18 while at their inner ends an angular heel 19 is positioned, 80 through perforations 20 of which the mount-ing pintles 16 extend. The extensions of 75 the arm heels 19 project inwardly as illus-trated in Fig. 3 when the arms are posi-tioned outwardly extended in perpendicular 85 relations with respect to the gunwale and by this arrangement it will be noted that when so positioned the heels prevent the arms from approaching each other nearer than their operative parallel planes.

A float 21 is adapted to be positioned be-tween each pair of outrigger arms and is 90 connected to a central eye 22 upon the plate 13 by means of two chains 23 secured to the said eye and which after passing through similar eyes 24 on the lower sides of the arms 17 are attached to opposite eyes 25 95 upon the float.

Each of the floats 21 is provided with a transverse passage 26 for accommodating

oppositely extending ratchet bars 27 which have their outer ends beveled as at 28 for engagement with the teeth 29 upon the end portions 30 of the outrigger arms 17, upon 5 a pair of which arms the float 21 is slidably mounted by means of spaced lugs 31 through which the arms extend and which lugs are positioned out of alinement with each other so as to allow an oscillating 10 movement of the float. The bars 27 are provided with pins 32 upon their inner ends adapted for reception within opposite eccentrically arranged slots 33 of an operating disk 34 which is adapted to be turned by 15 means of a shaft 35. The said shaft 35 is provided on its outer end with a head 36 having a kerf 37 and by means of which the shaft 35 may be partially revolved for withdrawing the bars 27 from their engagement with the teeth 29. The shaft head 36 is positioned in a socket 38 in the inner edge of the float 21. An expansion spring 40 is positioned between the inner ends of the arms 27 for normally projecting the same. 20

25 By this arrangement it will be evident by viewing Fig. 1 of the drawings that when the float 21 is operatively positioned adjacent the outer end of the outrigger arms 17, the said float may slightly oscillate when 30 resting upon the water as seen in Fig. 2, while by releasing the arms 27 by means of turning the shaft head 36, said arms are released and capable of being separated to assume the folded position also illustrated 35 in Fig. 1 and during which outward swinging movement of the arms, the chains 23 act to pull the float 21 inwardly to assume a suspended vertical position adjacent the plate 13 when the carrying arms flatly engage 40 the side of the boat adjacent the gunwale thereof and are retained in such position by being seated within suitable hooks 39 adjacent the opposite ends of the hull. 45

The outrigger arms 17 are preferably 50 formed of resilient material to allow of their being slightly bent when unfolded against the side of the hull but readily assuming their operative positions when hinged outwardly. With the outrigger in 55 its inoperative position, it is only necessary to release the arms from the hooks 39 and to move the same slightly inwardly toward each other and to position the arms between the lugs 31 of the float and then to push the float outwardly upon said arms whereby the ratcheting engagement between the bars 27 and the rack teeth 29 firmly locks the arms oppositely positioned contacting the said float and by means of the chains 23. 60

65 It will thus be seen that the floats 21 with the terminal floats 18 of the arms constitute a manner of imparting equilibrium to the boat while either or both of the outriggers may be employed.

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

What I claim as new is:—

1. An outrigger comprising a bracket 75 adapted for attachment to the gunwale of a boat, arms hinged at the opposite ends of said bracket and having teeth adjacent their outer ends, floats upon the free ends of said arms, a float mounted for oscillation between said arms, ratcheting bars carried by said float and normally contacting said teeth when positioned therebetween.

2. An outrigger comprising a bracket adapted for attachment to the gunwale of 85 a boat, arms hinged at the opposite ends of said bracket and having teeth adjacent their outer ends, floats upon the free ends of said arms, a float mounted for oscillation between said arms, ratcheting bars carried 90 by said float and normally contacting said teeth when positioned therebetween, eyes upon said arms, chains secured between said float and bracket and running through said eyes and a releasing means for said bars.

3. An outrigger comprising a bracket adapted to be secured to the gunwale of a boat, a depending plate upon said bracket, outrigger arms having angular heels hinged to the opposite ends of said bracket and adapted for movement in parallelism with each other and away from each other, a float, non-aligning lugs upon the opposite edges of said float and positioned upon said arms with said arms between the said lugs, 100 chains engaging said arms and connected between said float and plate whereby inward movement is imparted to said float upon the separation of said arms.

4. An outrigger comprising a bracket 110 adapted to be secured to the gunwale of a boat, a depending plate upon said bracket, outrigger arms having angular heels hinged to the opposite ends of said bracket and adapted for movement in parallelism with 115 each other and away from each other, a float positioned for oscillating between said arms, chains engaging said arms and connected between said plate and float, ratcheting means between said float and arms and releasing mechanism for said ratcheting means.

5. An outrigger comprising a mounting bracket, arms hinged thereto, an oscillating float slidably mounted upon said arms, connecting means between said bracket and float whereby said float moves inwardly when said arms assume their inoperative positions.

6. An outrigger comprising a mounting bracket, arms hinged thereto, an oscillating float slidably mounted upon said arms, connecting means between said bracket and float whereby said float moves inwardly when said arms assume their inoperative positions, ratcheting means between said float and arms adapted for locking said float ad-

jacent the ends of said arms in the operative position. 10

In testimony whereof I affix my signature in presence of two witnesses.

FRANK KRATKY.
